UNITED STATES PATENT OFFICE.

CHARLES V. RICHEY, OF WASHINGTON, DISTRICT OF COLUMBIA, ASSIGNOR TO PHONE-
CALL RECORDER COMPANY, A CORPORATION OF DELAWARE.

TELEPHONE METERING SYSTEM.

1,266,714.

Specification of Letters Patent.

Patented May 21, 1918.

Application filed July 11, 1914, Serial No. 850,486. Renewed October 2, 1917. Serial No. 194,415.

To all whom it may concern:

Be it known that I, CHARLES V. RICHEY, citizen of the United States, residing at Washington, in the District of Columbia, have invented certain new and useful Improvements in Telephone Metering Systems, of which the following is a specification, reference being had therein to the accompanying drawing.

10 My invention relates to telephone line control apparatus of the type disclosed in my prior Patents No. 1,037,053 of August 27, 1912, No. 1,063,599, June 3, 1913, and No. 1,067,274, July 15, 1913. The present system 15 is an improvement over the former systems in a number of respects particularly from the standpoints of simplicity of construction, and increased efficiency of operation.

The system of my prior patents aforesaid, 20 comprises in combination with the usual substation circuits, a register, means for actuating the register responsive to current of a special character from the central station, a lock and key control device controlling the 25 talking circuit and operable at the will of the subscriber for enabling and disabling the talking circuit and enabling and disabling the register, additional means under the control of the central station operator for enabling 30 said talking circuit for special calls, means for signaling the central station operator independently of closure of the talking circuit and hence without unlocking the lock-out device, whereupon the central station operator can permit special or emergency 35 calls such as calls for information, fire alarms, and the like. In this system the circuit of the register actuating device is closed only when the lock-out device is unlocked and the talking circuit enabled by 40 the subscriber, whereby the central station operator cannot falsely register a call against any subscriber, and yet the subscriber cannot prevent the operator from 45 making proper registry of calls for he necessarily enables the register when he enables the talking circuit. The subscriber or any one else cannot converse otherwise except through special permission of the central station operator as aforesaid. Thereby 50 the use of the phone by unauthorized persons for unauthorized purposes is absolutely prevented, and one of the great troubles of subscribers eliminated.

The present system accomplishes the same 55 results in a more efficient and reliable manner, and by use of simplified apparatus. The improvements have particularly to do with the elimination of the mechanical complications of the former system, and the substitution therefor of electrical and electromagnetic means. In addition to performing all the functions of the mechanical parts, the electrical and electromagnetic means perform other functions such for instance as 60 shutting ringing current out of the receiver and the prevention of false registration of a call in case the receiver is removed from its hook during the period ringing current is applied to the line by the central station 65 operator to call the subscriber.

In the accompanying drawings I show diagrammatically the best embodiments of my invention now known to me, but it is to be understood at the outset, that my invention is capable of other embodiments by those skilled in the art without departing in anywise from its generic spirit.

The various elements of the system are characterized as follows, the parts being 80 identified by the reference letters by which they are designated in the drawings.

(L—L') The subscribers' lines.

(T) The substation transmitter.

(P) The primary of the induction coil 85 which is connected in series with the transmitter T across the lines L—L'.

(R) The substation receiver.

(S) The secondary of the induction coil connected in series with the receiver R and 90 across the lines L—L'.

(G) The substation ringer.

(A) The register, which may be of the Veeder or any other desired type.

(B—B') The actuating magnets of the 95 register.

(C) The lever through which the register A is actuated from the magnets B—B'.

(D) The upper end of lever C which is movable longitudinally thereof to connect 100 and disconnect the same with the register through the pin and slot connection shown, the pin being on the end of the usual actuating arm of the register.

(E) A locking button connected with the 105 upper end D of lever C to operate the same up and down to connect and disconnect the register from lever C.

- (F) A key controlled lock by means of which the locking button E can be locked in depressed or register disabling position.
- (H) A part connected with the locking button E to be reciprocated thereby.
- (I) A group of contacts operated by the part H.
- (J—J') A pair of relays controlling the connections of the register actuating magnets B—B' and the substation receiver R.
- (K) A part connected with operating lever C for movement thereby.
- (M) A group of contacts controlled thereby.
- 15 (N) The emergency call key or button.
- (O) A pair of contacts controlled thereby.
- The circuit connections between the various elements of the apparatus of the system are fully understood from a description of 20 the operation of the system. The operation is as follows:
- As illustrated, the parts are in the relation which they occupy when the subscriber has unlocked his phone for calls. Upon 25 taking the receiver R from its hook he closes the talking circuit as follows: line L, primary P, conductor 10, receiver hook contacts 11 and 12 which are now closed, transmitter T, conductor 13, contacts 14—15 of group I associated with locking button E, and conductor 16 to line L'. This results in 30 indicating a call at the central station. The central station operator in answering it, having ascertained that the called line is 35 idle, effects the connection and impresses ringing current upon the called line. Ringing current upon the called line operates the usual substation ringer G. Ringing current then applied to the calling line however 40 traverses the following path and results in the operation of the register A to register a call. Commencing at line L, ringing current traverses primary P, conductor 10, now 45 closed contacts 11, 17 of the receiver hook, over conductor 19, through winding of relay J, conductor 21, condenser 22, and conductor 23 to line L'. Relay J opens the circuit of receiver R at its normally closed contacts 24 and closes the circuit of the register actuating magnet B at its normally 50 open contact 25 as follows; line L, primary P, conductor 10, branch conductor 26, contacts 27 of relay J', conductor 28, contacts 25 of relay J, conductor 29, magnet B, and line L'. Since in the up-standing position 55 of the lock-out button E the register A is connected with lever C through its upper end D, the register is actuated and the call recorded properly. The arrangement of the lever C is such that it remains in its operated positions, and hence additional applications of ringing current to the calling line during the continuance of a given call have no further effect upon the register, and it is impossible for the operator to register more 60

than the one call during the continuance of the same. The subscriber having concluded his conversation he hangs up his receiver whereupon he closes a restoring circuit for the restoring magnet B' of the register lever C as follows; line L, primary P, conductor 10, conductor 30, normally closed contacts 31, conductor 32, magnet B', conductor 33, contacts 34 of group M operated to closed position by the prior movement of lever C, conductor 35 and line L'. Lever C is thereby returned to its normal position, without in this case operating the register since the register is operable on the forward movement of the lever only.

Having completed the calls he desired to make, by simply depressing the lock-out button E, the subscriber disables his telephone set for use by any one else except for special or emergency calls. This is because 85 upon depression the button E is locked in depressed position by the spring lock F, and in its depressed position moves the part H to normally open the talking circuit previously traced at contacts 14 and 15. When contact 14 leaves contact 15 however, it makes contact with a third contact 36 of group I which partially closes a shunt around the now open contacts 14 and 15 by way of conductor 37 and normally open contacts 38 90 of the group M controlled by the register actuating magnet B. In its depressed position the button E uncouples the register A from the actuating lever C whereby calls cannot be registered against him by unauthorized persons attempting to use the phone, or by the central station operator. The register A cannot be operated by any one until the key to lock F has been applied to release the button E. This key is in the possession 105 of the subscriber.

However in case of emergency, any one having access to the phone may call the central station operator by depressing the special call button N once or several times. Through contacts O this closes primary winding P across lines L—L' through the resistance of any suitable value preferably about 500 ohms. The central station operator receives a call, and distinguishing it 110 from the usual call either by its intermittent character (impressed by pressing the button N intermittently) or by the fact that there is no answer when she listens in, applies ringing current to the line whereupon 115 register actuating magnet B is actuated and the talking circuit closed at contacts 38. The party making the special call, can then make his wants known to the operator and if the call is one authorized, such as a police, fire 120 call or the like, the operator will give the desired connection. Otherwise she will not for the reason that it is impossible for her to effect proper registry of the call at the subscriber's station, register A being uncou- 125 130

pled from its actuating magnet as aforesaid. At the conclusion of the call, the register actuating lever C is restored to normal as before over the circuit closed by the hook 5 contacts 31.

In order to prevent the energization of magnet B should the subscriber when called lift his receiver during the application of ringing current to his line the relay J' is 10 made to lock itself on ringing current supplied through the normally closed contact 31 of the switch-hook. The initial energizing circuit of relay J' may be traced as follows: Line L, P, 10, 30, 31, 32, J', 22, 23 and back 15 over line L'. The relay J' upon energization then opens the circuit of magnet B at contact 27 and locks itself through its normally open contact in the following circuit: Line L, P, 10, 26, normally open contact of J', J', 20 22, 23 and back over line L'.

It is to be noted that in cases where the capacity of the ringing generator is low, the margin of difference between the branch circuits through the transmitter and relay J 25 or J' may be increased by placing a retardation coil bridged by a condenser in series with the transmitter, the said coil and condenser being suitably proportioned or turned to offer very little impedance to the high 30 frequency pulsations produced by the transmitter while offering high impedance to the low frequency ringing current.

Having thus described my invention what I claim is:

35 1. In a telephone exchange system having a central office containing line terminals and connective apparatus therefor, with operator's listening and ringing means, a substation equipment comprising the following 40 instrumentalities: a ringer and condenser, a receiver and a switch hook adapted to connect the receiver to line, a transmitter adapted to be energized with current supplied from the central station, means for 45 disabling the transmitter circuit at the will of the subscriber, means for enabling transmitter use in emergency calls at the will of the operator at the central station, and means responsive to a normal call by ringing current to prevent operation of said enabling device when the call is answered.

50 2. In a telephone exchange system having a central office containing line terminals and connective apparatus therefor, with operator's listening and ringing means, a substation equipment comprising the following instrumentalities: a ringer and condenser, a receiver and a switch hook adapted to connect the receiver to line, a transmitter

adapted to be energized with current supplied from the central station, means for disabling the transmitter circuit at the will of the subscriber, means for enabling transmitter use in emergency calls at the will of the operator at the central station, a call meter, 60 means operable with said enabling means to actuate the call meter, and means responsive to a normal call by ringing current to prevent operation of said enabling device when the call is answered. 65

70 3. In a telephone exchange system having a central office containing line terminals and connective apparatus therefor, with operator's listening and ringing means, a substation equipment comprising the following instrumentalities: a ringer and condenser, a receiver and a switch hook adapted to connect the receiver to line, a transmitter adapted to be energized with current supplied from the central station, means for 80 disabling the transmitter circuit at the will of the subscriber, means for enabling transmitter use in emergency calls at the will of the operator at the central station, a call meter, means operable by said enabling 85 means to actuate said call meter for each outgoing call, and a relay responsive to incoming call current at the substation, adapted to disable said enabling means as long as said call current is being received. 90

95 4. In a telephone exchange system having a central office containing line terminals and connective apparatus therefor, with operator's listening and ringing means, a substation equipment comprising the following instrumentalities: a ringer and condenser, a receiver and a switch hook adapted to connect the receiver to line, a transmitter adapted to be energized with current supplied from the central station, means for disabling the transmitter circuit at the will of the subscriber, means for enabling transmitter use in emergency calls at the will of the operator at the central station, a call meter, means operable by said enabling 100 means to actuate said call meter for each outgoing call, and a pair of controlling relays adapted to cut off ringing current from the substation receiver, and also to disable the enabling device and prevent operation 105 of the meter if the call is answered while the ringing current is still being received.

In testimony whereof I affix my signature in presence of two witnesses.
